CLAIM

The ornamental design for a basket, as shown and described.

DESCRIPTION

FIG. 1 is a front elevation of a basket showing my new design, the rear side elevation being the mirror image of the front elevation;

FIG. 2 is a right side elevation thereof, the left side elevation being the mirror image of the right side elevation;

FIG. 3 is a top plan view thereof; and

FIG. 4 is a bottom plan view thereof.

FIG.1

FIG.2

FIG.3
